CLAMPING MEANS FOR TRAYS OR THE LIKE

Filed Jan. 10, 1931

Inventor:
Frank Glantz
By Maurice S. Bayne
Attest.

UNITED STATES PATENT OFFICE

FRANK GLANTZ, OF CHICAGO, ILLINOIS

CLAMPING MEANS FOR TRAYS OR THE LIKE

Application filed January 10, 1931. Serial No. 507,809.

This invention relates to a novel and improved clamping means for a tray or the like, and more particularly to a self-adjusting clamp by means of which a tray or the like 5 may be readily and securely attached to a table leg, or the like, regardless of the shape of the same.

One object of the invention is to produce a simple, attractive and convenient card table, 10 or the like, accessory which is provided with a novel self-adjusting clamping means by means of which it may be quickly fastened to card table leg or the like, in such position as not to obstruct the playing surface of the 15 table, said clamping means being adapted for attachment to the leg of a table or the arm of a chair regardless of the shape of the same or the size of the same within certain limits.

Another object of the invention is to produce a device of the character described, 20 which consists of few and simple parts that may be readily and easily manufactured and assembled along lines convenient for low cost production, and which will at the same 25 time be attractive in appearance and highly efficient for carrying out the purposes for which it is designed.

A further object of this invention is to produce a device of the character described 30 which consists in a horizontally disposed member having a pair of gripping jaws provided on one end thereof, and a horizontally disposed tray provided at the other end thereof, and a spiral spring means disposed in said 35 horizontally disposed member for forcing said jaws into operative clamping relation with each other.

A still further object of this invention is to produce a novel and improved clamping 40 means consisting of a fixed tubular member, one end of which is provided at diametrically-opposite points with two horizontal slits, that portion of the member lying on either side of said slits being bent at right angles 45 to said member to form a fixed jaw, and a curvilinear movable jaw adapted for co-operating with said fixed jaw for clamping therebetween the leg of a table or the like, said movable jaw having one end thereof received in the tubular member for sliding

movement therein, and a spiral spring means for urging the movable jaw towards the fixed jaw.

With the foregoing and other objects in view, which will appear as the description 55 proceeds, the invention consists in certain novel features of construction, arrangement, and combination of parts, hereinafter more fully described, illustrated in the accompanying drawings and particularly pointed out in 60 the appended claims, it being understood that various changes in the form, proportion, size, shape and minor details of the structure may be made without departing from the spirit or sacrificing any of the advantages of the invention. 65

For the purpose of facilitating an understanding of my invention, I have illustrated in the accompanying drawings a preferred 70 embodiment thereof, from an inspection of which, when considered in connection with the following description, my invention, its mode of construction and many of its advantages should be readily understood and appreciated. 75

Referring to the drawings, in which similar characters of reference are employed to indicate corresponding parts throughout the several figures of the drawings:

Figure 1 is a view in perspective of a device 80 embodying my invention, the same being shown attached in place on the arm of a chair, the latter being shown in dotted lines;

Figure 2 is a longitudinal sectional view 85 taken through the same; and

Figure 3 is a sectional view taken on line 3-3 of Fig. 2, and looking in the direction of the arrows.

In carrying out my invention, as herein shown, I employ a tubular hollow member, 90 generally designated by the reference character 10, said member being of any suitable material, such as metal or the like, and being provided at one end thereof with the elbow portion 11, which portion may be as shown in the drawings, formed integral with the member 10, or if desired, the same may be secured in any suitable and well known manner to the member 10. The open end of 95 the elbow portion 11, is provided with inter- 100

nal threads as shown at 12, for the purpose of receiving therein in threaded relation a suitable tray 13, or the like. The tray is provided with the projection or boss 14, which 5 is provided with the exterior threads for screwing the same into the open end of the elbow portion 11. The projection 14, is also provided with a depending lug 15, which is for a purpose to be presently more fully described.

The member 10, is provided adjacent the free end thereof at diametrically opposite points with two horizontal slits, and the portions of the member 10, lying on either side 15 of the said slits are bent at right angles to form the flanges 16 and 17, which flanges are vertically disposed and are in alignment with each other. These flanges 16 and 17 go to make up the fixed jaw of the gripping means 20 for attaching the device to a table leg or the like. To prevent the marring of the table leg or arm of the chair 30 (represented by broken lines in Fig. 1), to which my improved device is adapted to be attached, the 25 fixed jaw 16—17, is provided on its outer face with a felt pad 18.

In order to yieldingly grip the table leg, I provide the movable jaw which is generally designated by the reference character 19, and 30 which is of a shape and curvature as shown in the drawings. The said movable jaw is provided on the inner end thereof with a suitable hook member 21, which hook member is received within the member 10, the body portion 35 of the movable jaw extending outwardly from the hook member and extending through a longitudinally disposed slot 23, provided in the side of the member 10. The said slot 23, terminates at a point intermediate 40 the ends of the member 10, and the end wall of the slot is adapted for limiting the inward movement of the movable jaw. The said movable jaw is bent as shown at 22, to form almost a right angle with said hook portion 45 21, said bent portion acting as a hinge against the edge of the slot to facilitate in the opening up of the movable jaw member 19. The free end of the movable jaw 19, is bent outwardly as shown at 20, to facilitate in the 50 slipping of the gripping means in place around any suitable support. A pin 24 is provided adjacent the bent portion 22, for limiting the movement of the movable jaw 19, in a clockwise direction.

55 In order to yieldingly grip the support to which the device may be attached between the jaws 16—17 and 19, the latter jaw is urged toward the former by a helical spring 26, housed within the member 10. The said spring 26, has one end 27, thereof secured to the lug 15, and the other end 28, thereof secured to the hook portion 21. It will be noted that the free end 20, of the movable jaw extends a considerable distance beyond the plane of the member 10, thus permitting

the jaws to grip an object of considerable size, and regardless of the shape of the object, as the said movable jaw is curved in such a manner as to adopt itself around a square, oblong or curved surface. A suitable 70 tubing of rubber, or the like, designated by the numeral 25, is provided on the movable jaw 19, for preventing the marring of the surface of the object to which the device may be attached.

75 It will be readily apparent that the device is self-adjusting and may be quickly slipped in place with a single movement without necessitating the use of any fastening means, such as screws, bolts, or the like. Also it will be noted that the device comprises only a few simple parts, which may be readily and quickly assembled without the necessity of any tools, or the like. Although, the ash tray 13, has been shown in the drawings, it is to be understood that any other suitable tray, may be used, such for example as a flat tray for holding a glass, a pack of cards, or the like. My improved gripping means may also be used for securing a lamp in place on the edge of a bed, table or the like, as well as for any purpose that the same may be adapted for.

80 It is believed that my invention, its mode of construction, and assembly, and many of its advantages should be readily understood from the foregoing, without further description, and should also be manifest that while a preferred embodiment of the invention has been shown and described for illustrative 85 purposes, the structural details are, nevertheless, capable of wide variation within the purview of my invention as defined in the appended claims.

90 What I claim and desire to secure by Letters Patent of the United States is:—

95 1. A clamping means for a tray, comprising a horizontal tubular member, one end of said tubular member being provided with diametrically-opposite slits, the portions of said member lying on either side of said slits, being bent at right angles to form a fixed gripping jaw, a complementary movable gripping jaw carried and guided by the said horizontal member, a spring for urging the said movable jaw towards the fixed jaw, said spring being housed in said tubular member, and a tray carried by said tubular member.

100 2. A clamping means comprising a tubular member, one end of said tubular member being provided with diametrically-opposite slits, the portions of said member lying on either side of said slits being bent at right angles to form a fixed gripping jaw, a complementary movable jaw of curved formation carried and guided by the said tubular member, one end of said movable jaw being received in said tubular member, that portion of said movable member adjacent the said inner portion received in said tubular mem- 105

ber extending through a slot provided in the side wall of said tubular member for sliding movement therein, and a spring for urging the said movable jaw towards the said fixed jaw.

3. A clamping means of the character described, comprising a tubular member having a fixed gripping jaw provided on one end thereof, a complementary movable gripping jaw carried by said tubular member, the said movable jaw being of curved formation and having the major portion of the body thereof extending beyond and surrounding the said fixed jaw on all except one side thereof, the inner end of said movable jaw being received in said tubular member through a longitudinal slot provided in the side wall of the tubular member, and a spring for urging said movable jaw towards the fixed jaw, and a bent portion provided adjacent the inner end of the movable jaw said bent portion being adapted to act as a hinge against the inner edge of said longitudinal slot, whereby said movable jaw may pivot about said inner edge.

In testimony whereof I affix my signature.
FRANK GLANTZ.
